No. 870,563.

PATENTED NOV. 12, 1907.

W. KINDT.
PORTABLE STACK COVER.
APPLICATION FILED MAY 22, 1906.

UNITED STATES PATENT OFFICE.

WILLIAM KINDT, OF BELLEVILLE, KANSAS.

PORTABLE STACK-COVER.

No. 870,563.

Specification of Letters Patent.

Patented Nov. 12, 1907.

Application filed May 22, 1906. Serial No. 318,138.

To all whom it may concern:

Be it known that I, WILLIAM KINDT, a citizen of the United States, residing at Belleville, in the county of Republic and State of Kansas, have invented certain 5 new and useful Improvements in Portable Stack-Covers, of which the following is a specification.

My invention relates to improvements in portable stack covers, my object being to provide protection for hay, grain etc., against the deteriorating effects of the 10 elements.

The cover is adjustable both in height and width to accommodate stacks of different sizes, and may be quickly placed in position for immediate use, or taken apart for transportation from one part of the field to another. When in position it effectually prevents the 15 stack from being overturned by wind, excludes rain, snow and frost and thus renders skilful topping of the stack unnecessary.

With these ends in view the invention may be said to 20 consist in the novel construction, combination and arrangement of parts hereinafter described, illustrated in the accompanying drawing, and pointed out in the appended claims.

In order that the invention may be fully understood 25 reference will now be made to said drawing, in which:—

Figure 1 represents a perspective view of my cover in 30 position upon a stack. Fig. 2 is an enlarged vertical section of same with the lower portion of the center-pole broken away. Fig. 3 is a vertical section taken on line III—III of Fig. 2 with the conical top removed. Fig. 4 is a detail perspective view of an apron forming part of the invention. Fig. 5 is an enlarged inverted section taken on line V—V of Fig. 1 showing the detachable ends of a hoop forming part of the invention.

In carrying out the invention I employ a center-pole 35 1, around which the stack is formed, for supporting the stack-cover and preventing the stack from being overturned by wind. The lower end of said pole is preferably secured in the ground and its upper end 2 is tapered for the reception of a tapering ferrule 3 which snugly but detachably fits said upper end. Ferrule 3 is provided with a pair of upwardly-extending arms 4 carrying a shaft 5 (here shown as a bolt) upon which a pair of sheave-wheels 6 are journaled, said sheave-wheels being held apart by a spacing-block 7. The upper terminals of arms 4 are turned outwardly and downwardly for the reception of a conical cap 8 secured thereon and forming the apex of the cover for the purpose of preventing rain, snow and frost from entering 50 the cover through a sleeve 9 loosely embracing ferrule 3 and provided near its upper end with a peripheral flange 10. Said sleeve is adjustably-supported by a pair of hoisting-cables 11 extending in opposite directions over sheave-wheels 6 and attached at their upper 55 terminals to the lower portion of the sleeve. The upper portions of the hoisting-cables are oppositely-dis-

posed as shown in Fig. 2, so that when their lower portions are grasped for the purpose of raising or lowering the sleeve the latter will not bind against the pole and thus add to the labor of adjusting said sleeve and the 60 stack-cover carried thereby. By thus rendering the top of the stack-cover adjustable it may be raised or lowered to accommodate stacks of different heights, or if a storm should arise while the stack is in course of construction the cover may be lowered to the desired 65 point for the protection of the grain or hay.

12 designates a conical top for the cover consisting, preferably, of canvas in the shape of a truncated cone, and detachably secured to the upper portion of the sleeve by a gathering rope 13 drawn around the canvas 70 above flange 10 to prevent the upper portion of the top from slipping downwardly upon the sleeve. The lower portion of top 12 is expanded by a hoop 14 having overlapping ends one of which has a button 14^a for engagement with a slot 14^b in the other end. Thus said ends 75 may be readily disconnected so that the hoop can be expanded preparatory to removing it and top 12 from pole 1.

In order that the hoop may be expanded as above described the overlapping sides of top 12 are laced together by hooks 15 and a rope 16 the lower end of which latter is wound about the button 14^a and prevents the latter disengaging slot 14^b. The upper end of rope 16 is attached to rope 13 so that when the former is unlaced the latter may be unwrapped from the 85 upper end of top 12 if it is desired to also remove said top from the sleeve.

18 designates a bail having a swiveled connection with the upper end of the sleeve and adapted to be engaged by a hay-fork when it is desired to lift top 12 in 90 position upon the stack or remove it therefrom. The body of this bail is of a size to loosely embrace cap 8, so that when it is raised in an upright position its ends lift the cap and ferrule entirely off the pole along with the cover, but when it is turned aside as shown in Fig. 95 1 its raising or lowering will adjust the cover without affecting the ferrule and cap.

The sides of the stack are protected by aprons 19 provided at their upper ends with hooks 20 for detachably engaging the hoop, so that one or more of said aprons 100 may be removed when it is desired to take material from the stack. Said aprons flare toward their lower ends so that their sides may be let out, and still overlap, to accommodate a large or conical stack, and their lower corners are provided with ropes 21 which are drawn 105 in opposite directions around the stack and tied to prevent wind getting beneath the cover and blowing it from the stack. If desired weights may be attached to said ropes to assist in holding the cover in position when exposed to a gale.

Rain is prevented from entering the cover at the top of the aprons by a flange 22 integral with the lower por-

tion of top 12 and overlapping the upper edges of said aprons.

23 designates a transverse pin adapted to engage any one of a series of holes 24 in the pole, so that the cover 5 may be positively supported at any desired height. It also assists in preventing the cover from being blown from the pole and the stack when cables 11 are attached to its projecting terminals 23a.

In practice, the cover may be placed in position 10 upon the pole and supported at the upper portion thereof by pin 23, preparatory to building the stack around the pole by hand, or if a hay-fork is to be employed in building the stack the cover is left off until the stack is finished, and then lifted in position by 15 means of said fork, the bail 18 affording a convenient means for engagement with the fork.

After the material which formed the stack has been used, the cover may be removed in its entirety from the pole by means of the hay-fork, or, if preferred, it 20 may be lowered to the ground and removed from the pole by hand after the top has been unlaced and the ends of the hoop unfastened.

Having thus described my invention what I claim and desire to secure by Letters-Patent, is:—

25 1. In a stack cover, the combination with the pole having a tapered upper end, a tapered ferrule adapted to fit said end and having a pair of arms extending upwardly and turned outwardly and downwardly, sheave-wheels journaled between said arms, a spacing-block between them, 30 and a conical cap secured on their upper ends; of a sleeve surrounding and larger than said ferrule, a stack-cover proper carried by said sleeve, two ropes leading upward between said ferrule and sleeve, passing in opposite directions over said wheels, and having their terminals secured to the lower portion of the sleeve, and additional means for adjusting the vertical position of said sleeve.

2. In a stack cover, the combination with the pole, a ferrule adapted to fit said pole and having a pair of arms extending upwardly and turned outwardly and downwardly, sheave-wheels journaled between said arms, and a conical cap secured on their upper ends; of a sleeve surrounding and larger than said ferrule, a stack-cover proper carried by said sleeve, two ropes leading upward between said ferrule and sleeve, passing in opposite directions over said wheels, and having their terminals secured to the sleeve, a series of transverse holes being formed through the pole, and a pin adapted to be inserted in any of said holes and to have both ends project beneath the sleeve and in position to be engaged by said ropes.

3. In a stack-cover, the combination with the pole, a ferrule adapted to fit its end and having a pair of arms extending upwardly and turned outwardly and downwardly, sheave-wheels journaled between said arms, and a conical cap secured on their upper ends; of a sleeve surrounding and larger than said ferrule, a stack-cover proper carried by said sleeve, two ropes leading upward between said ferrule and sleeve, passing in opposite directions over said wheels, and having terminals secured to the sleeve, and a bail whose ends are swiveled in the 60 sleeve near its upper extremity and whose body is of a size to loosely surround the cap, for the purpose set forth.

4. In a stack-cover, the combination with the pole, a ferrule adapted to fit its upper end and having a pair of arms extending upwardly and turned outwardly, sheave-wheels journaled between said arms, and a conical cap secured on their upper ends; of a sleeve surrounding and

larger than said ferrule, a stack-cover proper carried by said sleeve, two ropes leading upward between said ferrule and sleeve, passing in opposite directions over said wheels, and having their terminals secured to the sleeve, a pin removably inserted through a hole in the pole below the lower end of the sleeve, and a bail swivelly connected to its upper end and loosely embracing the cap, for the purpose set forth. 70

5. In a stack-cover, the combination with a pole, a ferrule removably mounted on its upper end, a sheave-wheel carried by the ferrule, and a conical cap rigidly supported by the ferrule above the wheel; of a sleeve larger than the pole and ferrule, a rope leading upward between the ferrule and sleeve and over the wheel and connected with the sleeve, a stack-cover proper whose top is gathered around the upper portion of the sleeve, and a bail whose body loosely embraces the cap and whose ends are inturned and swiveled in the sleeve, as and for the purpose set forth. 75

6. In a stack-cover, the combination with a pole, a ferrule removably mounted on its upper end, and a conical cap carried by the ferrule; of a sleeve larger than the ferrule but smaller than the cap, a stack-cover proper whose upper end is gathered around the sleeve so as to be protected by the cover, means for adjusting from the ground the height of the sleeve with respect to the ferrule, and a bail swiveled to the sleeve and loosely embracing the cap so that it may be turned aside and adjusted vertically from above to permit the descent of the sleeve, but when raised it will also raise the cap and ferrule. 80

7. In a stack-cover, the combination with a pole, a ferrule removably mounted on its upper end, and a conical cap carried by the ferrule; of a sleeve larger than the ferrule but smaller than the cap, a stack-cover proper whose upper end is gathered around the sleeve so as to be protected by the cover, means for sustaining the sleeve at different heights with respect to the pole, and a bail swiveled to the sleeve and loosely embracing the cap so that it may be turned aside and adjusted vertically from above to permit the descent of the sleeve, but when raised it will also raise the cap and ferrule. 85

8. A portable stack-cover comprising a conical cap and sleeve adapted to be sustained by a pole, the sleeve having a peripheral flange near its upper end beneath said cap, a flexible top having a peripheral flange and split radially to produce overlapping edges, a gathering rope around said top and sleeve above the flange on the latter, an expansible hoop within the flange of the top having button-and-slot connection at its ends, hooks on the top near its edges, a lacing rope engaging said gathering rope and adapted to be laced over said hooks and wound about said button, aprons forming the sides of the cover and having hooks removably engaging said hoop, and ropes for securing the lower ends of the aprons in place. 90

9. A portable stack-cover comprising a conical cap and sleeve adapted to be sustained by a pole, the sleeve having a peripheral flange near its upper end beneath said cap, a flexible top having a peripheral flange, a gathering rope around said top and sleeve above the flange on the latter, an expansible hoop within the flange of the top having button-and-slot connection at its ends, aprons forming the sides of the cover and having hooks engaging said hoop, and ropes for securing the lower ends of the aprons in place. 95

In testimony whereof I affix my signature, in the presence of two witnesses.
